UNITED STATES PATENT OFFICE.

JOHN BERTRAM LACY, OF CHICAGO, ILLINOIS.

GRAVITY AIR CIRCULATOR.

Application filed April 3, 1922. Serial No. 549,096.

To all whom it may concern:

Be it known that I, JOHN BERTRAM LACY, a subject of the King of England, and a resident of Chicago, in the county of Cook and State of Illinois, have invented a new and useful Improvement in Gravity Air Circulators, of which the following is a full, clear, and exact description.

My invention relates to improvements in gravity air circulators for refrigerators, and it consists in the combinations, constructions, and arrangements herein described and claimed.

An object of my invention is to provide a gravity air circulator of the character described which is more simple in construction than shown in my previous air circulating systems and in which the air is better circulated than in the previous constructions.

20 A further object of my invention is to provide a construction of the character described in which the air is cooled and delivered at a point adjacent the ceiling of the room, thus permitting the cooled moving air 25 to fall directly upon the contents of the room.

A further object of my invention is to provide a construction of the character described in which a dead air space is disposed 30 between the current of warm air entering the cooling space and the current of cool air delivered therefrom.

A further object of my invention is to provide a construction of the character described by means of which a relatively small current of warmer air is admitted to the cooling space and which is distributed over a relatively large cooling area and delivered through a relatively large opening when 40 fairly cooled. The action of the relatively thin current of warmer air striking the cooling coils is such that only a minimum deposit of frost is left upon the cooling pipes.

Other objects and advantages will appear in the following specification, and the novel features of the invention will be particularly pointed out in the appended claims.

50 My invention is illustrated in the accompanying drawings, forming part of this application, in which—

Figure 1 is a sectional view of an embodiment of my invention, and

Figure 2 is a top plan view of the mechanism shown in Figure 1.

55 In carrying out my invention, I make use of a supporting rack 1 which is suspended

from the ceiling 2 of the cooling room 3 and the side wall 4. The rack 1 consists of a plurality of vertical supports 4' of angle iron which are fastened directly to the ceiling 2, as shown at 5, and a plurality of vertical angle iron supporting members 6, which are secured directly opposite the supports 4', and horizontal cross pieces 8 of angle iron are riveted as shown at 9, at each end to the supports 4' and 6, respectively. The horizontal supporting members 8 are relatively close together so that cooling pipes 10, through which a brine or chemical cooling agent flows, are approximately disposed at a distance of four inches from center to center. Reference to Figure 2 will show that the relative positions of the pipes 10 extend from wall to wall in the room 3 and are in parallel relation to the wall 4.

A metal sink 11 is disposed at a slight inclination from the supports 6 to the supports 4 and runs the entire length of the pipes 10. The sink 11 terminates at its lower end 12 in a gutter (see Figure 1). The upper and opposite end of the sink 11 is in a vertical plane and extends in substantially parallel relation to the wall 4 behind the tier of pipes 10. A baffle of insulating material is disposed immediately beneath the pipes 10 and at a slight angle from the horizontal plane. This baffle 13 is of wood, suitably covered by a metal casing, and it is mounted so that it inclines upward as it approaches the supporting members 4' from which it is supported by means of bolts 14.

Unlike the sink 11, however, the insulating baffle 13 extends the entire width of the room, while the sink 11 merely extends beneath the pipes 10. A dead air space 15 is provided by means of a hollow sheet metal casing 15', closed at each end and a cross section through which resembles an isosceles triangle. This casing 15', providing the dead air space, is entirely closed, and is supported upon the supporting members 4' by means of brackets 16 and 17 so that one of its sides 19 lies in a plane parallel to the wall 4. The uppermost side of the casing 15' extends laterally beyond the adjacent side 19 toward the wall 4 substantially as shown at 18.

The space between the sink 11 and the baffle 13 is filled with an insulating material as shown at 18a.

From the foregoing description of the various parts of the device, the operation thereof may be readily understood. Let us assume that a cooling agent is flowing through the pipes 10 and that air is free to circulate in the room 3. The warm air in the room will rise to the ceiling 2 and that air which is adjacent to the dead air space 15 will gradually flow over the extension 18 between the dead air space 15 and the ceiling 2, which is a relatively narrow opening, into the space 16^a occupied by the cooling pipes 10.

The air thus flowing into the space 16^a will be admitted in a relatively thin stream and when once in the space 16^a, will be distributed. When the air comes into contact with the pipes 10, it will be cooled quickly because the heated air has been distributed over a larger area and when cooled the air will pass out through the space between the outer end of the baffle 13 and the bottom of the dead air space 15.

As the cool air leaves the cooling space 16^a in the manner described, it will be permitted to fall upon the contents of the room and will not, as in the constructions in use at present, be delivered at a point adjacent the bottom of the room. The cooled air, because it is distributed at a point adjacent to the top of the room, will not be apt to absorb much heat before it reaches the objects which are to be cooled.

It will also be noted that this stream of cooled air is directed toward the center of the room and not toward the walls where it is less needed.

The baffles 13 serves as a means to prevent condensation under the sink 11 and also aids materially in the circulation of air in the room.

The particular provision of the dead air space 15 has also been found to greatly increase the efficiency of the circulation of the air, since the air readily passes over the extension 18 and down through the coils 10, there being no opportunity for the formation of eddy current adjacent the casing 15' as has been the case where an angular trough was substituted for the casing 15' and which did not provide a dead air space.

I claim:

1. A gravity air circulation system for a cooling room comprising a cooling means disposed adjacent the ceiling and a side wall of said cooling room, an inclined sink disposed beneath said cooling means, an insulating baffle disposed beneath said sink and inclined downwardly toward said side

wall, and a dead air casing resembling a triangle in cross section disposed in front of said cooling means and at a relatively short distance from the ceiling, the upper corner of said triangular casing being closer to said side wall than the lower corner. 60

2. A gravity air circulation system comprising a bank of pipe coils for containing a cooling medium, said bank of coils being supported adjacent the ceiling of a cooling room, an inclined sink disposed beneath said pipe coils and arranged to incline downwardly toward the front, an insulating baffle disposed beneath said sink, and a dead air casing disposed adjacent the ceiling of said room in front of said pipe coils, said casing resembling a triangle in cross section. 70

3. A gravity air circulation system comprising a bank of pipe coils for containing a cooling medium, said bank of coils being supported adjacent the ceiling of a cooling room, an inclined sink disposed beneath said pipe coils, an insulating baffle disposed beneath said sink, and a dead air casing disposed adjacent the ceiling of said room in front of said pipe coils in a manner so that one of its corners overhangs its adjacent corner, said casing formed to resemble an isosceles triangle in cross section and arranged so that its shortest side faces said pipe coils. 80

4. A gravity air circulation system comprising a bank of pipe coils for containing a cooling medium, said bank of coils being supported adjacent the ceiling of a cooling room, an inclined sink disposed beneath said pipe coils, said sink being formed with a gutter at its lowermost point running the full length thereof, an insulating baffle disposed beneath said sink, and a dead air casing disposed adjacent the ceiling of said room in front of said pipe coils, said casing resembling an isosceles triangle in cross section. 90

5. In a gravity air circulator having a plurality of pipe coils for containing a cooling medium disposed adjacent the ceiling of a cooling room, of a casing for providing a dead air space disposed in front of said coils, a sink disposed beneath said pipe coils and arranged to incline downwardly toward the front tier of said pipe coils, and an insulating baffle disposed beneath said sink and inclined upwardly toward the front tier of said pipe coils, the space between said sink and said baffle being filled with an insulating material. 105

JOHN BERTRAM LACY. 110
